UNITED STATES PATENT OFFICE.

ISSACHAR COZZENS, OF GLENCOVE, NEW YORK.

KNEE-PROTECTOR FOR STOCKINGS.

SPECIFICATION forming part of Letters Patent No. 693,115, dated February 11, 1902.

Application filed July 14, 1900. Serial No. 23,553. (No model.)

To all whom it may concern:

Be it known that I, ISSACHAR COZZENS, a citizen of the United States, and a resident of Glen-
cove, in the county of Nassau, Long Island,
5 State of New York, have invented certain new
and useful Improvements in Knee-Protectors
for Stockings, of which the following is a speci-
fication.

My invention relates to knee-protectors;
10 and its object is to cover the knees of stockings
when on the leg to protect the same from
wear.

My invention is particularly adapted for
children's use, and is so constructed as to con-
15 form to the shape of the leg in every position
it may assume, in a similar manner to that of a
well-fitting stocking, closely binding against
the stocking and to a casual observer present-
ing nothing further to the eye than the stock-
20 ing itself.

In the accompanying drawings, Figure 1
illustrates a side view of a knee-protector made
in accordance with my invention. Fig. 2 is a
25 side elevation of a leg covered with a ribbed
stocking and a knee-protector, of a slightly
different form from that shown in Fig. 1, cov-
ering the knee of the stocking.

Similar letters represent like parts in both
the figures.

30 The knee-protector consists of a tube made
from a ribbed textile fabric, the ribs of the
protector extending continuously from end
to end of the same. The protector A (shown
35 in Fig. 1) consists of three portions, a middle
portion B and two ends portions C and D. At
the circumferential lines a and b where the
end portions C and D begin the longitudinal
40 ribs are made finer or narrower and close to-
gether, thus somewhat contracting or making
of smaller circumference said parts C and D
to the part B and also making said parts C
and D less flexible than the central part B.
45 This construction permits the ends of the pro-
tector fitting and holding snugly above and
below the knee, while the central part B, which
encircles the knee, will be flexible enough to
permit all the necessary bend and play of the
50 leg at the knee-joint. The ribbed construc-
tion provides ample elasticity to the protec-
tor, so that it will always cling closely to the
leg in every position the leg assumes, and

avoids the necessity of making the central
portion of the protector of a swelled and bulg-
ing shape, as are those of some knee-protectors
now used. My knee-protectors are par-
55 ticularly adapted for use by children over
their stockings, and as such stockings are
usually made of a ribbed textile fabric simi-
lar to my knee-protector the fact that such a
protector is worn over the stocking will be 60
only perceptible to a close observer. Each
end portion of the protector is provided with a
selvage edge c to prevent raveling. This sel-
vage is the usual finish at the end of a knit
fabric, and is known in the art as a "welt." 65
About half-way between the two end por-
tions C and D the part B is preferably of
slightly larger circumference than the rest of
the protector, and from said circumferential
line d the protector gets gradually smaller 70
toward the end portions C D. This construc-
tion prevents too much binding at the knee,
but permits it to hold closely to the leg both
at the knee and above and below the same.
In the knee-protector A' shown in Fig. 2 the 75
finer ribbed upper portion C is dispensed
with.

The protector may be held up by the same
garter or supporter that holds up the stock-
ing.

80 My knee-protector being of the shape and
flexible character above described and of
uniform material throughout its circumfer-
ence, it may be turned around, so as to bring
over the knee any part of the circumference 85
that may be desired in case any part of it
should become worn or for any other reason.
As both the ends C and D are made alike in
the form shown in Fig. 1, this form could be
worn with either end up; and it may, there- 90
fore, after having been worn one way, be
turned upside down and worn the other way.

What I claim as new, and desire to secure
by Letters Patent, is—

1. A knee-protector consisting of a tube of 95
textile fabric longitudinally and continuously
ribbed from end to end and each end provided
with a selvage.

2. A knee-protector consisting of a tube of
textile fabric longitudinally ribbed from end 100
to end and gradually tapering or decreasing
in circumference from its middle portion to

its two ends, and each end provided with a selvage.

3. A knee-protector consisting of a tube of textile fabric longitudinally ribbed from end 5 to end, with the ribs finer or narrower at one end portion, and each end provided with a selvage.

4. A knee-protector consisting of a tube of textile fabric longitudinally and continuously 10 ribbed from end to end with the ribs finer or narrower at one end portion, and each end provided with a selvage.

5. A knee-protector consisting of a tube of textile fabric longitudinally ribbed from end 15 to end with the ribs finer and narrower at the

end portions, and each end provided with a selvage.

6. A knee-protector consisting of a tube of textile fabric longitudinally and continuously ribbed from end to end with the ribs finer and 20 narrower at the end portions, and each end provided with a selvage.

In testimony whereof I have signed my name to this specification in the presence of two subscribing witnesses.

ISSACHAR COZZENS.
